JEWELRY FINDING

Richard Charles, Townhouse East, Apt. K5,
Manlius, N.Y. 13104

Filed Dec. 9, 1970, Ser. No. 26,374

Term of patent 14 years

Int. Cl. D11—01

U.S. Cl. D45—1

The figure on the drawing is a front perspective view of a jewelry finding showing my new design, the back thereof being plain and unornamented.

I claim:

The ornamental design for a jewelry finding, substantially as shown and described.
